UNITED STATES PATENT OFFICE.

BERTRAND B. KAHN, OF CINCINNATI, OHIO, ASSIGNOR TO THE ESTATE STOVE COMPANY, OF HAMILTON, OHIO.

DESIGN FOR A GLOWER-REFLECTOR.

53,916.

Specification for Design.

Patented Oct. 7, 1919.

Application filed April 25, 1919. Serial No. 292,751. Term of patent 14 years.

To all whom it may concern:

Be it known that I, BERTRAND B. KAHN, a citizen of the United States, residing at Cincinnati, county of Hamilton, State of Ohio, have invented a new, original, and ornamental Design for a Glower-Reflector, of which the following is a specification, reference being had to the accompanying drawing, forming a part thereof.

Figure 1 is a front view and Fig. 2 a side

view of a glower-reflector showing my new design.

I claim:

The ornamental design for a glower-reflector, as shown.

BERTRAND B. KAHN.
